(57) **CLAIM**

The ornamental design for a clip-on tool holder, as shown and described.

DESCRIPTION

FIG. 1 shows an front isometric view of a clip-on tool holder in accordance with the present design, shown here with a non-limiting example of a tool, more specifically a tape measure, attached to the holder, the tool forming no part of the claimed design.

FIG. 2 shows another front isometric view of the clip-on tool holder of FIG. 1.

FIG. 3 shows a rear isometric view of the clip-on tool holder of FIG. 1.

FIG. 4 shows a front elevation view of the clip-on tool holder of FIG. 1.

FIG. 5 shows a rear elevation view of the clip-on tool holder of FIG. 1.

FIG. 6 shows a left side elevation view of the clip-on tool holder of FIG. 1.

FIG. 7 shows a right side elevation view of the clip-on tool holder of FIG. 1.

FIG. 8 shows a top plan view of the clip-on tool holder of FIG. 1; and,

FIG. 9 shows a bottom plan view of the clip-on tool holder of FIG. 1.

The dash-dot broken lines represent the boundary of the claim and form no part of the claimed design. The dash-dash broken lines represent environment that forms no part of the claimed design.

1 Claim, 5 Drawing Sheets
